HEAD FOR A DUST MOP

Howard A. Anderson, Pittsburgh, Pa., assignor to Bissell Inc., Grand Rapids, Mich., a corporation of Michigan

Filed Feb. 9, 1968, Ser. No. 10,515

Term of patent 14 years

Int. Cl. D7—06

U.S. Cl. D49—21

FIG. 1 is a perspective view of a head for a dust mop incorporating the new design, the portions shown in phantom lines being illustrative only and forming no part of the design;

FIG. 2 is a top plan view thereof;

FIG. 3 is a side view thereof;

FIG. 4 is a view of the design of FIG. 3, taken from the left end thereof; and

FIG. 5 is a view of the design of FIG. 3, taken from the right end thereof.

I claim.

The ornamental design for a head for a dust mop, substantially as shown and described.
